UNITED STATES PATENT OFFICE

GEORGE H. KEELEY, OF MILFORD, ILLINOIS.

MUD OR DUST PROTECTOR FOR BUGGIES.

SPECIFICATION forming part of Letters Patent No. 657,601, dated September 11, 1900.

Application filed March 3, 1900. Serial No. 7,229. (No model.)

To all whom it may concern:

Be it known that I, GEORGE H. KEELEY, a citizen of the United States, residing at Milford, in the county of Iroquois and State of Illinois, have invented a new and useful Mud or Dust Protector for Buggies, &c., of which the following is a specification.

The invention relates to improvements in mud and dust protectors for buggies, carriages, and other vehicles.

One object of the present invention is to improve the construction of covers or protectors for the boxes or bodies of buggies, carriages, and other vehicles and to provide a simple and comparatively-inexpensive one capable of protecting the body from mud, dirt, water, and the like, and thereby obviate the necessity of washing the body and avoid scratching or otherwise injuring the varnish and finish of the vehicle by such operation.

A further object of the invention is to provide a device of this character adapted to be readily placed on and removed from the body or box of the vehicle and capable of being securely retained in place without employing fastening devices, the use of which on the vehicle will be objectionable when the cover or protector is not in position.

The invention consists in the construction and novel combination and arrangement of parts hereinafter fully described, illustrated in the accompanying drawings, and pointed out in the claims hereto appended.

In the drawings, Figure 1 is a perspective view of a protector constructed in accordance with this invention and shown applied to the body or box of a buggy. Fig. 2 is a similar view of the body portion of the protector removed from the body or box. Fig. 3 is a longitudinal sectional view, the parts being arranged as shown in Fig. 1. Fig. 4 is a transverse sectional view. Fig. 5 is a detail perspective view of the shield for protecting the back and sides of the seat. Fig. 6 is a detail perspective view of one of the resilient clasps.

Like numerals of reference designate corresponding parts in all the figures of the drawings.

1 designates a protector or cover designed to be applied to the box or body 2 of a buggy, carriage, or other vehicle and constructed of suitable material, such as oil-cloth, and con-

forming to the configuration of the box or body, as clearly illustrated in Fig. 1 of the accompanying drawings. The body or cover, 55 which is approximately rectangular, is composed of sides 3, a front 4, and rear sections 5, overlapped to form a back, as illustrated in dotted lines in Fig. 2. The front 4 of the protector or cover is extended above the sides 60 3 to fit the dashboard and is provided with an upper inverted pocket 6, receiving the upper extended portion of the dashboard and composed of inner and outer portions, as clearly illustrated in Fig. 3, the inner portion 7 being arranged over the inner face of the extended portion of the dashboard and extending downward from the top thereof to the upper edges of the sides 3. The sides 3 are provided at their tops with central extensions 8, projecting upward, as clearly 65 shown in Fig. 2, and conforming to the configuration of the side supports for the seat. The extensions 8 are provided at their front and rear ends with flaps 9, having button-holes and adapted to be buttoned or otherwise secured to the supports or extensions 10 of the sides of the box or body at the ends of the seat. The sides are provided in advance and in rear of the extensions 8 with short inner portions 11 and 12, depending within the body or box 2 and extending downward from the upper edges thereof, as clearly illustrated in Fig. 4 of the drawings. By this construction the sides of the protector cover the entire outer faces of the sides of the body or box 80 and extend over the upper edges of the same and extend downward a considerable distance over the inner faces of the sides in advance and in rear of the seat. The front and rear 90 portions of the sides are substantially inverted-U-shaped in cross-section, and the overlapped sections 5 of the back of the protector are of substantially the same construction, being composed of inner and outer portions and supported on the upper edges of the back of the body or box. The sides and the back of the protector are provided with resilient clasps 13, approximately U-shaped 95 and secured within the material of which the protector is constructed, whereby they are adapted to clamp the body or box without marring the same. The clasps, which are constructed of steel or other resilient mate-

rial, are composed of inner and outer sides 14 and 15, the inner sides being shorter than the outer sides, as clearly illustrated in Fig. 6 of the accompanying drawings. The sides of the clasps extend downward from the top of the protector to the lower edges of the inner and outer portions of the sides and back and are adapted to hold the protector securely on the box or body.

- 10 The sides and back of the seat 17 are protected by a shield 18, buttoned or otherwise secured in position, as illustrated in Fig. 1 of the drawings, and provided with side extensions 19, disposed horizontally and conforming to the configuration of the sides of the seat. The shield is substantially rectangular, as illustrated in Fig. 5 of the drawings. Its upper portion conforms to the configuration of the back of the seat, and its lower portion 15 depends below the same to the lower edges of the inner portions of the sides 3. The upper portion of the shield is provided at the top and side edges of the buttonhole 20 to engage buttons 21 of the back of the seat, and those buttons usually employed for securing the back curtain to the seat may be utilized for attaching the shield. The side extensions 19 of the shield are provided at their upper edges with buttonholes 22 and extend inward 20 over the sides or arms of the seat and engage buttons 23 thereof, and a button 24 is preferably provided at the lower edge of each of the extensions 19 to engage buttonholes of the same and buttonholes or eyelets of the extensions 8. When the protector and the shield are detached from the box or body and the seat, they may be compactly rolled together and kept within the body or box for instant use.
- 25 It will be seen that the device is simple and comparatively inexpensive in construction, that it is adapted to be readily applied to all kinds of vehicles, and that it is capable of protecting the same from mud, dirt, water, and the like and of preventing the scratching and other injury to the finish of vehicles resulting from the operation of cleaning them. It will also be apparent that the device is securely retained in place without the employment of fastening devices, which injure or otherwise impair the use of the box or body when the protector is not in use. Furthermore, by the particular construction of the clasps, which have inner short sides and outer 30 long sides to conform to the construction of the protector and which extend to the lower edges of the outer sides, as clearly shown in Figs. 3 and 4, it will be apparent that the protector is effectually prevented from blowing upward or away from the body or box and exposing the latter.

What is claimed is—

1. A protector for vehicles comprising the front, back and sides composed of inner and outer portions and supported upon the upper

edges of the body or box of the vehicle, the back being composed of overlapped sections, substantially as described.

2. A protector for vehicles comprising the front, back and sides composed of inner and outer portions and supported upon the upper edges of the box or body of the vehicle and provided with approximately U-shaped clasps located at the sides and back, substantially as described.

3. A protector for vehicles comprising the front having an inverted pocket to receive the dashboard, the sides arranged on the exterior of the sides of the box or body and provided with inner depending front and rear 80 portions located in advance and in rear of the seat, and the back having inner and outer portions, substantially as described.

4. A protector for vehicles composed of the front back and sides consisting of inner and outer portions and supported upon the upper edges of the body or box, said sides being provided between their ends with extensions located at the ends of the seat, and a shield arranged at the back of the seat and provided 90 with opposite extensions arranged above the said extensions, substantially as described.

5. A protector for vehicles comprising the front back and sides, and the shield designed to be arranged on the back of the seat and provided at the sides of the box or body of the vehicle, with extensions located at the arms or ends of the seat, substantially as described.

6. A protector for vehicles comprising the front, back and sides composed of inner and outer portions and the approximately U-shaped clasps located at the back and sides and conforming to the configuration of the inner and outer portions of the same and extending to the lower edges of the outer portions, whereby the latter are held closely against the body or box of the vehicle and are prevented from blowing upward and exposing the same, substantially as and for the purpose described.

7. A protector for vehicles conforming to the configuration of a box or body and composed of inner and outer portions, the inner portions being shorter than the outer portions, and the approximately U-shaped clasps having short inner sides and long outer sides to conform to the inner and outer portions of the protector, the outer sides of the clasps being extended to the lower edges of the outer portions of the protector to hold the same closely against the body or box, substantially as described.

In testimony that I claim the foregoing as my own I have hereto affixed my signature in the presence of two witnesses.

GEORGE H. KEELEY.
